(57) **CLAIM**

The ornamental design for an LED light assembly, as shown and described.

DESCRIPTION

FIG. 1 is a perspective view of the first part of the LED light assembly;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the second part of the LED light assembly;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof;

FIG. 17 is a perspective view of the third part of the LED light assembly;

FIG. 18 is another perspective view thereof;

FIG. 19 is a front view thereof;

FIG. 20 is a rear view thereof;

FIG. 21 is a left side view thereof;

FIG. 22 is a right side view thereof;

FIG. 23 is a top plan view thereof;

FIG. 24 is a bottom plan view thereof;

FIG. 25 is a perspective view of the first part and the second part of the LED light assembly assembled together;

FIG. 26 is a perspective view of the second part and the third part of the LED light assembly assembled together;

FIG. 27 is a perspective view of the first part and the third part of the LED light assembly assembled together;

FIG. 28 is a perspective view of the first part, the second part and the third part of the LED light assembly assembled together; and,

FIG. 29 is a perspective view of the first part, the second part and the third part of the LED light assembly shown separately.
